UNITED STATES PATENT OFFICE.

AURELIUS STEWARD, OF BRIDGEPORT, CONNECTICUT, ASSIGNOR TO THE WHEELER & WILSON MANUFACTURING COMPANY, OF SAME PLACE.

SMOCKING ATTACHMENT FOR SEWING-MACHINES.

SPECIFICATION forming part of Letters Patent No. 642,015, dated January 23, 1900.

Application filed March 17, 1899. Serial No. 709,502. (No model.)

To all whom it may concern:

Be it known that I, AURELIUS STEWARD, a citizen of the United States, and a resident of Bridgeport, in the county of Fairfield and State of Connecticut, have invented certain new and useful Improvements in Smocking Attachments for Sewing-Machines, of which the following is a specification.

The object of my invention is to produce by mechanical means a folded and stitched fabric as usually made by hand, commonly called "smocking," which is used for ornamental purposes in the manufacture of garments and which retains the fabric in such a series of folds or purls as to cause it to present ornamental designs capable of different modifications and appearances as the material is differently held or restrained in its application to the garment.

In the accompanying drawings, which form a part of this specification, Figures 1 to 10, inclusive, show all of the parts of my apparatus in perspective. Fig. 1 shows the retaining-clamp E, together with its permanently-attached pivot-pins and handle C, but disconnected from its associate parts the better to show its construction. Fig. 2 is the hinge-bar D disconnected. Fig. 3 is the frame A, fully dismembered, except of its permanently-attached hinge-blocks B and B' and handle C, to better show its construction. Fig. 4 is the spring-clamp disconnected. Fig. 5 is the fabric holder or carriage complete consisting of the before-mentioned parts as assembled for use. Figs. 6, 7, and 8, respectively, are the gage, presser-foot, and throat-plate of the sewing-machine as modified to suit the purposes of my invention. Fig. 9 is the apparatus complete with fabric attached and as in use. Fig. 10 is the carriage complete, but removed from the machine, as for disengaging and reengaging the work. Fig. 11 is a section of the stitched fabric or smocking, and Fig. 12 the same when differently constrained to show changed appearance in the figures under such condition.

The frame A (see Fig. 3) is of sheet metal as thin as consistent with moderate stiffness, its front edge provided with a series of equidistant parallel-sided interstices or slots a a, &c., extending inwardly from and at right angles with the edge, and also provided at each end with hinge-blocks B and B', the

latter being extended upward and suitably shaped to serve also as a handle, as shown at 55 C. The back edge of frame A is turned upward to impart greater stiffness and curved to form a recess into which the spring-clamp F may fall to retain the fabric, as hereinafter described.

The retaining-clamp E (see Fig. 1) is of same material as frame A with front edge also provided with slots (shown at e e, &c.) exactly the same distances apart as in frame A, and in addition has intermediate therewith 65 a series of holes intended only to remove the stock to prevent interference with the presser-foot of the machine when in use. It also has its rear edge turned upward to impart greater stiffness and has attached thereto a spring- 70 handle c, while the front or slotted edge is overturned to an angle of, say, forty-five degrees (for purposes to be hereinafter explained) and is provided at each end with securely-attached pivot-pins e' and e', all 75 shown in Fig. 1.

The hinge-bar D (see Fig. 2) is provided with two holes (shown at d and d') near each end of same.

The spring-clamp F (shown in Fig. 4) has 80 its ends turned inwardly to enter holes therefor in hinge-blocks B and B', by which means it is pivotally connected with the frame A.

When parts are connected as for use, the pivot-pins b and b' of hinge-blocks B and B' 85 (not shown in B') enter pivot-holes d and d', and pivot-pins e' and e' of the retaining-clamp E enter pivot-holes d' and d' in the hinge-bar D, thus hinging the retaining-clamp E to the hinge-bar D and the latter to frame A, all as 90 shown in Fig. 5 and as required in operation. When so placed, the slots e e of the retaining-clamp E are located exactly intermediate (longitudinally) with the slots a a of the frame A for purposes hereinafter described. 95 As this combination of parts is for the purpose of holding and carrying the fabric, for convenience I will term the same the "carriage."

The presser-foot G, Fig. 7, is not sufficiently 100 unlike those of ordinary sewing-machines to require special description.

The throat-plate I, Fig. 8, is constructed without the usual apertures for the feed-dog, (the latter not being employed with this device,) and there is provided at each side of—

that is, before and after—the needle a slightly-raised projection, as shown at *i* and *i*, which I term "stops," which are of such size as to fit loosely into the slots *a a*, &c., of the 5 frame A.

My attachment is preferably used in connection with what is known to the trade as a "zigzag sewing-machine;" but as the stitches must appear only in clusters the feed-dog is 10 removed that the fabric may not be advanced while being stitched. By the well-known lateral vibratory action of the needle in such machines it will be seen that the stitches will be passed through two holes only, and by the 15 controlling mechanism of the machine the vibratory action is so regulated as to overcast only a sufficient number of threads of the fabric to give the finished product the necessary stability. Preparatory to stitching the first 20 row the end of the fabric to be operated upon is passed between the spring-clamp F and the frame A and turned back over the latter beneath the hinge-bar D and the retaining-clamp E, when light pressure upon the spring-handle C of the latter causes it to engage the 25 overturned edge of the frame A, and an upward pressure upon the yielding spring-clamp F causes it to compress the interposed fabric into the concaved upturned portion of the 30 frame A, thereby clamping the fabric to prevent displacement while being stitched. With fabric thus attached the carriage is placed upon the bed-plate of the sewing-machine, with its slotted edge beneath the presser-foot 35 G and against the gage H, as shown in Fig. 9, with two of the slots *a a*, &c., of the frame A embracing the stops *i i* upon the throat-plate I, the stops being so situated that when entering these slots the intermediate slot will 40 properly present itself for the passage of the needle. After making the requisite number of stitches the machine is stopped, the presser-foot raised, and by means of the handle C the carriage slightly lifted and advanced 45 one step, when, being impeded and stopped by the entrance of the stops *i* and *i* into the next slots, another cluster of stitches is formed and this repeated across the fabric. Although the fabric is usually interposed, 50 yet owing to its yielding qualities it does not prevent the entrance of the stops sufficiently to at once indicate to the operator when the carriage has advanced to correct position. To disengage and reengage the fabric for successive lines of stitches, the spring-clamp F is pressed downward and the stitched material together with the retaining-clamp E and the hinge-bar D are all thrown forward into 55 position shown in Fig. 10, when the tongues 60 of the frame A are readily withdrawn from the recesses or pockets by which the stitching has caused them to be incased. In this position it will be seen that by the action of the hinge-bar D the retaining-clamp E has 65 been thrown forward clear of the frame A and that its tongues present a flat surface upon the fabric and the underlying table, and

when by means of its handle *c* the retaining-clamp is carried forward, and, if necessary, moved slightly endwise, its slots will embrace 70 the stitches and its tongues readily enter into the pockets from which those of the frame have been withdrawn, whereupon the hinge-bar D and the retaining-clamp E are turned back, carrying with them the then overlying 75 stitched fabric, the spring-clamp pressed upward, and the cloth again clamped in position, as shown in Fig. 9, thereby locating each successive line exactly parallel and intermediate with the preceding line of stitches. I 80 do not confine myself to the use of the hinge-bar D to perform this important function, as any mechanical construction will suffice by which the retaining-clamp E may be transferred from the forward position, where it 85 engages one line, to the backward position, where it retains the same in proper relation to the succeeding line of stitches. When the stitching is completed, the finished product presents on one side a succession of folds like 90 overlying tucks, while on the other and right side an aggregation of diamond-shaped cells appears, as seen in Fig. 11. If, however, the material be stretched crosswise of the lines of stitches, the cells or recesses are drawn 95 into shapes shown in Fig. 12 and if again released assume still another form, and different treatment producing other effects not necessary to explain; but in all cases the pleasing character of the effects is dependent 100 upon the uniform straightness of the lines of stitches in all directions, their equal and alternate placement in the succeeding rows, and the uniform depths of the cells, all of which are insured by the clamping devices 105 and methods herein described.

While this attachment may be used with zigzag sewing-machines of usual construction, it is used to best advantage with such as stop automatically after a predetermined number 110 of stitches, and though preferably used with zigzag machines of some character they are not a necessary requisite, as it is evident the carriage could be vibrated beneath the needle of an ordinary sewing-machine without 115 changing the character of my invention.

What I claim as my invention, and desire to secure by Letters Patent, is—

The frame A, provided with apertures *a a*, to receive a row of clusters of stitches, means 120 for forming said stitches, in combination with means whereby each successive row of said stitches will be placed the proper distance from, and the clusters properly intermediate, those of the succeeding row, substantially as 125 described.

Signed at Bridgeport, in the county of Fairfield and State of Connecticut, this 9th day of March, A. D. 1899.

AURELIUS STEWARD.
